UNITED STATES PATENT OFFICE.

HENRY R. WARFORD, OF MEMPHIS, TENNESSEE.

RERAILING FROG.

Application filed July 24, 1925. Serial No. 45,774.

To all whom it may concern:

Be it known that I, HENRY R. WARFORD, a citizen of the United States, residing at Memphis, in the county of Shelby and State of Tennessee, have invented certain new and useful Improvements in Rerailing Frogs, of which the following is a full, clear, and exact description, such as will enable anyone skilled in the art to make and use the same.

This invention relates to devices which will facilitate the rerailing of de-railed railway rolling stock. It relates more specifically to a rerailing frog which will rest on and engage the rail of a track to support one end of the frog and insure against lateral movement of the frog while a car is being moved thereover; which will rest on and solidly engage the tie to prevent longitudinal displacement; which will engage the rail to prevent vertical movement; and which will provide a broad base to prevent over-turning.

The objects of my invention are,

First, to make a frog which is adapted for use on either the inside or outside of the rail and is usable for replacing rolling stock from either direction.

Second, to make a frog one end of which will rest solidly upon the rail and be there held against lateral displacement, and the other end of which will rest solidly on a tie and so abut against same as to be held against longitudinal displacement.

Third, to make a frog which will be braced against overturning.

Fourth, to make a frog which will lock beneath the ball of the rail and be prevented thereby from vertical displacement.

I accomplish these objects as will be more fully hereinafter set out in the drawings, specification and claims.

In the drawings:

Fig. 1 is a side elevation of the rerailing frog as applied to one of the rails of the track.

Fig. 2 is a plan view of the frog shown in Fig. 1.

Fig. 3 is a section on the line III—III of Fig. 1 showing the means for locking the rerailing frog against vertical displacement.

Fig. 4 is a section on the line IV—IV of Fig. 2 showing the manner in which the end of the frog engages the rail.

Referring now to the drawings in which the various parts are indicated by numerals. 1—1 are railroad ties, 2 are tie plates thereon and 3 railroad rails resting on the tie plates, the customary spikes for fastening the rail to the tie not being shown.

The frog comprises a member substantially of rectangular cross section symmetrical about its transverse center. The top 4 is a plane surface with downwardly curved ends 5 forming approaches. The frog is of greatest depth at the center 6 from which point the under surfaces 7 converge similarly toward the top 4. The curvature of the upper surface of the ends is continued until it passes beyond the plane of the undersurface and the end 8 itself is extended below these undersurfaces and substantially at right angles to them to provide tie abutments adapted to come against the sides of the ties.

9 are laterally projecting lugs or members disposed one near each end, each of which members with the underside of the corresponding end is channeled out to form a frog end seat 10 which seat is adapted to rest on the top of the rail. This seat 10 is curved so that it will adjust itself to rails of varying height, the channelway being angularly disposed laterally to the body of the frog as shown by the dotted lines 11 in the plan view Fig. 2.

The undersurfaces 7 of either end are disposed at such angle to the top 4 and the seat 10 that when the seat 10 at one end rests on the top of a rail the opposite undersurface 7 forms a seat adapted to rest on the tie 1 and support that end of the frog. This supporting surface is broadened by laterally projecting flanges 12 the undersides of which are flush with and form an extension of the surfaces 7.

13 is a dog adapted to engage the underside 14 of the ball of the rail and to lock into the corner formed by the ball of the rail and the web 15 thereof. This dog preferably comprises a bolt 16 having a sleeve nut 17 thereon with a pointed end 18, which nut may be screwed out to engage the rail.

2
this bolt is formed with a T head 19 which is adapted to seat in a pocket 20 substantially at the longitudinal center 6 of the frog. The ends of this T head engage in 5 oppositely disposed grooves 21 and prevent accidental displacement of the dog. These grooves 21 may extend vertically and thence laterally, to one side of the frog, and may be left entirely open or if desired, it may be 10 closed after the insertion of the dog to prevent accidental removal of the dog thereafter. 22 are braces for the flanges 12.

In use, one end of the frog is placed on the rail and the opposite end rested on a 15 tie with the dog engaging the underside of the rail and the end 8 resting against the side of the tie. Similarly an identical frog is placed on the opposite rail. The frog shown in Fig. 2 is shown on the outside of 20 the rail. The corresponding frog to be used would therefore be placed on the inside of the opposite rail. After the frogs are placed the rolling stock to be rerailed is pulled forward until the wheels engage 25 the lower end of the frog and thereafter the wheels will climb the frog and drop into place on the rails as the rolling stock is further moved forward. During the movement 30 of the rolling stock over the frog there is a slight tendency for the frog to tip up when the wheel first hits the lower end of it, but this tipping is resisted by the dog. Similarly, as the wheel rolls off the frog on to the rail there is a similar tendency 35 to tip by reason of the curved under surface 10 of the rail seat. This tipping movement is likewise resisted by the dog.

It will of course be understood that the various details of construction may be 40 modified so long as such modifications do not depart from the scope of the invention as outlined herein.

Having now fully described my invention, what I claim and desire to secure by Letters 45 Patent in the United States is:—

1. A rerailing frog, comprising a body portion substantially rectangular in cross section and symmetrical about its longitudinal center, having a substantially flat upper surface, downwardly curved to provide 50 approaches thereto at each end, and its under surfaces each converging from the longitudinal center toward an end, said ends being continued and extending below, and 55 substantially at right angles to, said body portion to form tie abutments for said frog; a member projecting laterally from the side of the body portion, near each end, having an angularly disposed channel-way cut 60 therethrough and through the said ends to provide a rail seat, said rail seat being convex; flanges, oppositely disposed from said members, extending laterally from said body portion, and having their under surfaces flush with the under surface of said 65 body portion to form a continuation thereof, to form, with the under side of said body portion, a tie seat for said frog, and a centrally disposed dog adapted to interlock with the under side of the ball of the rail.

body portion and forming a continuation thereof, to form, with the underside of said body portion, a tie seat for said frog; and a centrally disposed dog adapted to interlock with the underside of the ball of the 70 rail.

2. A rerailing frog, comprising a body portion symmetrical about its longitudinal center, having a substantially flat upper surface, downwardly curved to provide approaches thereto at each end, and its under surfaces each converging from the longitudinal center toward an end, said ends being continued and extending below, and substantially at right angles to, said body 80 portion to form tie abutments for said frog; a member projecting laterally from the side of the body portion near each end, having an angularly disposed channel-way cut therethrough and through the said ends to 85 provide a rail seat; flanges, oppositely disposed from said members, extending laterally from said body portion, and having their under surfaces flush with the under surface of said body portion and forming 90 a continuation thereof, to form, with the underside of said body portion, a tie seat for said frog, and a centrally disposed dog adapted to interlock with the underside of 95 the ball of the rail.

3. A rerailing frog, comprising a body portion substantially rectangular in cross section and symmetrical about its longitudinal center, having a substantially flat upper surface, downwardly curved to provide 100 approaches thereto at each end, and its under surfaces each converging from the longitudinal center toward an end, said ends being continued and extending below, and substantially at right angles to, said body 105 portion to form tie abutments for said frog; a member projecting laterally from the side of the body portion near each end having an angularly disposed channel-way cut therethrough and through the said ends to 110 provide a rail seat; flanges, oppositely disposed from said members, extending laterally from said body portion, and having their under surfaces flush with the under surface of said body portion and forming a continuation 115 thereof, to form, with the under side of said body portion, a tie seat for said frog, and a centrally disposed dog adapted to interlock with the under side of the ball of the 120 rail.

4. A rerailing frog, comprising a body portion symmetrical about its longitudinal center, having a substantially flat upper surface, downwardly curved to provide approaches thereto at each end, and its under surfaces each converging from the longitudinal center toward an end, said ends being continued and extending below, and substantially at right angles to, said body 130

portion to form tie abutments for said frog; a member projecting laterally from the side of the body portion near each end, having an angularly disposed channel-way cut therethrough and through the said ends to provide a rail seat; and flanges, oppositely disposed from said members, extending laterally from said body portion and having

their under surfaces flush with the under surface of said body portion and forming a continuation thereof, to form, with the underside of said body portion, a tie seat for said frog.

In testimony whereof I have hereunto set my name.

HENRY R. WARFORD.
